(57) CLAIM

We claim the ornamental design for a “flexible sample of a countertop replica,” as shown and described.

DESCRIPTION

This application claims priority to U.S. patent application Ser. No. 12/748,215, filed Mar. 26, 2010, entitled “Kit Of Pre-Construction Samples For Replicating Construction Products,” and claims priority to U.S. patent application Ser. No. 12/605,116, filed Oct. 23, 2009, entitled “Kit Of Pre-Construction Samples For Replicating Construction Products,” both of which are herein incorporated by reference in their entirety.

FIG. 1 is a perspective view of a flexible sample of a countertop replica, and which shows our flexible sample of a countertop replica in one of its intended environments on an existing countertop.

FIG. 2 is a front end view of the flexible sample of a countertop replica shown in FIG. 1.

FIG. 3 is a top view of the flexible sample of a countertop replica shown in FIG. 1.

FIG. 4 is a left side view of the flexible sample of a countertop replica shown in FIG. 1.

FIG. 5 is a right side view of the flexible sample of a countertop replica shown in FIG. 1.

FIG. 6 is a rear end view of the flexible sample of a countertop replica shown in FIG. 1, taken from the lower end having the optional header.

FIG. 7 is a bottom view of the flexible sample of a countertop replica shown in FIG. 1 with an optional region having information regarding the countertop.

FIG. 8 is an alternative embodiment of the flexible sample of a countertop replica shown in FIGS. 1-7, in which the flexible sample includes a darker base countertop simulation than the flexible sample of FIGS. 1-7; and,

FIG. 9 is an alternative embodiment of the flexible sample of a countertop replica shown in FIGS. 1-7, in which the flexible sample includes a lighter base countertop simulation than the flexible sample of FIGS. 1-7.

The broken lines are only for illustrative purposes to show visible environmental structure and internal features, which form no part of the claimed design.
